ELECTRIC SEMICONDUCTOR DEVICES

John Albert Leno, London, England, assignor to International Standard Electric Corporation, New York, N.Y., a corporation of Delaware

Application February 16, 1955, Serial No. 488,561

Claims priority, application Great Britain March 25, 1954

9 Claims. (Cl. 317—235)

The present invention relates to the construction of electric semi-conductor devices, and concerns more particularly devices such as crystal triodes of the kind in which two fine wire electrodes or catswhiskers are placed in contact with the surface of a semi-conducting crystal, such as germanium.

In the case of crystal triodes, the points of the catswhiskers have usually to be placed very close together, and in order to obtain reproducible characteristics for the device, the spacing and pressure of the electrodes has to be carefully controlled.

The principal object of the present invention is to provide a construction for a crystal triode or similar device having at least two catswhisker electrodes, which will allow the required spacing to be conveniently and accurately obtained.

This object is achieved according to the invention by providing an electric semi-conductor device comprising a slice of semi-conducting material having a plurality of sharply pointed fine wire electrodes or catswhiskers making contact with one face of the slice, the spacing of the points of two of the said electrodes being determined by a thin membrane or sheet of insulating material, arranged therebetween, and arranged perpendicularly in contact with the said face, the ends of the said electrodes being inclined to the said membrane or sheet in such manner that substantially only the point of each electrode makes contact with the membrane or sheet.

The invention is concerned with a convenient form of construction for crystal triodes and similar devices, to which the principles described in the specification accompany the application of C. F. Drake for Metal Semiconductor, Serial No. 457,747, filed September 22, 1954, will be applied. Accordingly, in the present specification, full details of such matters as electro-forming, contact pressure, and methods of electrolytic pointing of catswhiskers are not given.

The invention will be described with reference to the accompanying drawings, in which:

Fig. 1 shows a top view of a crystal triode according to the invention;

Fig. 2 shows a partly sectioned side elevation of the crystal triode shown in Fig. 1;

Fig. 3 shows a top view of one of the parts of the crystal triode shown in Figs. 1 and 2;

Fig. 4 shows a sectional view at the line X—X of Fig. 3;

Fig. 5 shows a side view of a catswhisker assembly used in the crystal triode shown in Figs. 1 and 2;

Fig. 6 shows a top view of the catswhisker assembly shown in Fig. 5.

Fig. 7 shows a top view of an alternative form of the crystal triode; and

Fig. 8 shows a sectional view of Fig. 7, taken at the line Y—Y.

Reference will first be made to Figs. 1 and 2. The crystal triode is mounted on a body 1, made of some suitable high stability insulating material, such as glass,

2

or a ceramic material. The body 1 is fused or otherwise fixed into an annular metal ring 2 in the form of a channel. The body 1, also carries three metal sleeves 3, 4 and 5, which are fused or moulded into the body. 5 The central sleeve 4, is expanded into conical form at the upper end 6 and accommodates a metal rod 7, having a flat head 8, surrounded by a metal tube 9. The arrangement of the elements 7, 8 and 9 is shown more clearly in Figs. 3 and 4.

Between the lower part of the rod 7 and the head 8 is a conical portion 11, which fits the conical upper end 6 of sleeve 4, shown in Fig. 2. On the upper surface of the head 8, there is fixed by soldering or otherwise a slice 10 of semi-conducting material, such as germanium, and, resting symmetrically on, and perpendicularly to this slice, is a thin sheet or membrane 12 held in diametrically opposite slots of the tube 9. The sheet 12 may, for example, be made of mica or glass.

The semi-conducting slice 10 is fixed to the head 8 of the rod 7, with a suitable soldering alloy, and the assembly is then placed in a suitable jig and lapped down to the required thickness which may, for example, be from 0.005" to 0.030", according to the performance desired. The lapped face is then cleaned and etched to 20 produce a suitable surface, after which the head 8 of the rod 7 is fixed with a drive fit into the metal tube 9. The sheet or membrane 12 is next fitted into the slots of the tube 9 and secured with a suitable adhesive. The thickness to be chosen for the membrane 12 will depend 25 upon the characteristics required for the crystal triode. For example, if the crystal triode is required to operate at high frequencies, for example from 30 to 50 megacycles per second, the thickness of the membrane may need to be as small as 0.0005"; if, however, the device 30 is not expected to be used above about 1 megacycle per second, a suitable thickness would be about 0.002".

The completed sub-assembly shown in Figs. 3 and 4 is now fitted into the sleeve 4 (Fig. 2) and tightly pressed home, so that the conical surface of the portion 11 comes 40 closely into contact with the conical mouth 6 of the sleeve 4. The lower end of the rod 7 is soldered at 13 to the sleeve 4, thus making an assembly which is rigid in spite of differences between the diameters of the rod 7 and sleeve 4.

The crystal triode is now provided with two similar catswhisker assemblies, shown in Figs. 5 and 6. Each catswhisker assembly comprises a metal rod 14, having a circular hole drilled at the upper end to accommodate the catswhisker electrode 15, which is made from a fine 50 carefully straightened wire. This wire is fitted into the hole at the upper end of the rod 14, and is secured by swaging the upper end between V-shaped dies, thus giving it a square section. In this way, the catswhisker wire is firmly bonded into the rod 14.

55 The wire is then bent into the form shown in Fig. 5, and comprises a portion 16 at right-angles to the axis of the rod 13 and inclined portion 17 which makes an angle of 80° with the portion 16 as shown. The tip of the portion 17 is cut off at an angle of 25° with the axis of the portion 17, thus forming a chisel point. The point so produced should be as sharp as possible, and should be further sharpened by a suitable electrolytic process which is operated under carefully controlled conditions. The process used may, for example, be that described in the specification of application, Serial No. 457,747, mentioned above.

The diameter of the wire forming the catswhisker 15 may, for example, be of the order of 0.005". Various materials may be used for this wire: for example, platinum, Phosphor-bronze, silver, tungsten or platinum-ruthenium, and may be alloyed, if necessary, with small quantities of suitable significant impurities according to

the characteristics desired for the crystal triode. In the case of a crystal triode intended for use at high frequencies, satisfactory results have been obtained by using platinum-ruthenium for the emitter electrode and Phosphor-bronze for the collector electrode.

The two cats-whisker assemblies designed as described with reference to Figs. 5 and 6 are inserted into the tubes 3 and 5 shown in Fig. 2 in such manner that the points of the two cats-whiskers come on opposite sides of the membrane 12. The rods 14 and 18 should be spaced from the rod 7 in such manner that the ends of the catswhiskers will be pressed lightly against the membrane 12 when the rods are sliding in their corresponding sleeves. The assembly is located in a suitable jig (not shown), by means of which the rods 14 and 18 of the electrode assemblies can be adjusted vertically by means of micrometer screws. Care should be taken that the points of the catswhiskers are accurately opposite to one another on either side of the membrane 12. Each rod is then carefully lowered by means of the corresponding micrometer screw until the catswhisker makes contact with the surface of the crystal slice 10. Contact can be detected by arranging so that an electric circuit (not shown) containing an indicating instrument is completed when contact is made. The rod corresponding to the collector electrode is then adjusted in such manner that the point of the corresponding catswhisker presses upon the surface of the crystal with a force of about 0.2 gram. The rod corresponding to the emitter electrode is adjusted so that the catswhisker point presses upon the crystal surface with a force of 1.2 grams.

The contacts of the catswhiskers are now subjected to a suitable electro-forming process, according to the characteristics required for the crystal triode. Electro-forming processes are described for example in the specification of application, Serial No. 457,747, already referred to. The particular process to be used will depend on the characteristics required for the crystal triode.

After the completion of the electro-forming process, the force exerted by the collector electrode on the crystal is increased by about 0.4 gram, and that exerted by the emitter electrode by about 6 grams. The rods 14 and 18 are then secured in position by soldering preferably at both ends, as indicated at 19 and 20.

The amount of longitudinal adjustment of the rods 14 and 18 necessary to produce the required force pressing on the crystal surface will, of course, depend upon the mechanical properties of the wire of which the catswhisker are composed. When the material of this wire has been chosen, it is possible to calculate from the form of the wire, as shown in Fig. 5, the amount of movement of the rod which will produce a given force pressing on the surface.

In some cases, it may be desirable to protect the contacts by the use of some suitable organic insulating compound or wax with which the tube 9 may be filled.

The complete assembly is enclosed in a cylindrical metal cover 21, shown in Fig. 2, which fits the annular channel of the ring 2, as shown, and which may be secured therein, for example by soldering.

A slightly different arrangement is shown in Figs. 7 and 8. In this case, the main body of the device consists of a circular disc of insulating material 22, having a central recess 23, which accommodates the head 24 of a rod 25 which fits into a sleeve 26, moulded into the body 22. The crystal slice 27 is mounted on the head 24, in the manner already described. Two sheets or membranes 28 and 29 are secured at right angles in slots in the body 22, as shown, and rest perpendicularly on the crystal slice 27. Two catswhisker assemblies, similar to that shown in Figs. 5 and 6, are arranged in sleeves 30 and 31, moulded into the body 22 in such manner that the points of the catswhiskers make contact with the crystal in two opposite corners between the two sheets, as shown in Fig. 7. The thickness of these sheets is so

chosen that the points of the cats-whiskers will be separated by the required amount when arranged in this way. The adjustment of the contact pressures may be carried out in the manner described with reference to Figs. 1 and 2. If desired, the recess 23 may be filled with a suitable insulating compound, and a cover (not shown), similar to 21 shown in Fig. 1, may be secured in some suitable way.

It will be obvious that, if desired, additional catswhiskers (not shown) could be placed in either or both of the remaining corners between the membranes 28 and 29.

It should be pointed out that the use of an insulating sheet or membrane for separating two of the catswhiskers of a crystal triode or similar device has already been suggested. An example can be found, for instance, in U.S. application, Serial No. 174,693, filed July 19, 1950. In this case, however, while the membrane acts efficiently to prevent the electrodes from coming into contact, it does not necessarily provide a very accurate spacing between the points of the two electrodes.

This accuracy of spacing is obtained, according to the present invention, by shaping the end of the catswhisker, as shown in Fig. 5, so that it will be inclined to the membrane, whereby contact with the membrane occurs substantially only at the point of the catswhisker. Thus, when the radius at the point of the catswhisker is accurately determined by the electrolytic pointing process employed, the spacing between the points of contact of the two catswhiskers with the crystal surface on either side of the membrane will also be accurately determined.

Although germanium will generally be used as the semi-conducting material, the invention is not restricted to crystal triodes employing germanium; for example, silicon could be used instead of germanium.

Reference has been made above to the addition of small quantities of significant impurities to the material of a catswhisker. Such impurities may, for example, be phosphorus, arsenic, antimony, aluminium, indium or gold or mixtures of some of these.

While the principles of the invention have been described above in connection with specific embodiments, and particular modifications thereof, it is to be clearly understood that this description is made only by way of example and not as a limitation on the scope of the invention.

What I claim is:

1. An electric semi-conducting device comprising a slice of semi-conducting material, a plurality of sharply pointed fine wire electrodes positioned adjacent said slice with the points of said electrodes making contact with one face of said slice, two intersecting sheets of insulating material, each mounted between two of said electrodes perpendicular to and in contact with said face, the wire electrodes being inclined to said sheets with only the point of each electrode bearing against said sheets at an angle thereto and means for urging said electrodes against said face in a normal direction thereto, whereby said sheets determine the spacing of the points of said electrodes.

2. An electric semi-conducting device comprising a slice of semi-conducting material, a plurality of sharply pointed fine wire electrodes positioned adjacent said slice with the points of said electrodes making contact with one face of said slice, a thin sheet of insulating material mounted between two of said electrodes, perpendicular to said face, and in contact with said face, the wire electrodes being inclined to said sheet with only the point of each electrode bearing against said sheet at an angle thereto, means for urging said electrodes against said face in a normal direction thereto whereby said sheet determines the spacing of the points of said electrodes, a supporting body of insulating material, a first metal rod secured in said body, the slice of semi-con-

ducting material being mounted on the end thereof, additional metal rods each having one of the fine wire electrodes mounted on the end thereof, and elongated guide means secured in said body parallel to said first rod for supporting said additional rods parallel to said first rod and permitting longitudinal adjustment thereof prior to securing said additional rods to said guide means.

3. A device, according to claim 2, in which the first rod is provided with an enlarged head on which the said slice is mounted, further comprising a metal tube attached to said head and enclosing said slice and the ends of the fine wire electrodes.

4. A device, according to claim 3 in which the said metal tube is filled with a protective insulating compound.

5. A device, according to claim 2, further comprising a metal cover secured to the body and enclosing the slice of semi-conducting material and the electrodes.

6. A device, according to claim 3, in which the metal tube is provided with diametrically positioned slots parallel to the axis of said tube for receiving and securing it in perpendicular relation to the surface of the slice.

7. A device according to claim 2, further comprising an elongated sleeve secured in the support for supporting the first rod, said sleeve having a conical enlargement at the end thereof, said first rod having an enlarged head on which the slice is mounted and a conical portion between said head and the rod proper which engages said conical enlargement of said sleeve when

said rod is pushed into said sleeve, whereby said rod may be accurately centered therein.

5 8. A device, according to claim 2, in which each fine wire electrode has a first portion extending substantially at right angles to its supporting rod and an end portion bent towards said supporting rod at an angle of substantially 80° with respect to said first portion, and the point is bevelled at substantially 25° with respect to said end portion and away from said supporting rod.

10 9. The method of manufacturing an electric semi-conducting device having a slice of semi-conducting material mounted on a support and at least two fine wire electrodes also mounted on the support with the pointed 15 ends thereof in spaced point contact with a face of said slice which comprises adjusting each electrode in a direction normal to said face until the point thereof exerts a predetermined force on said face, subjecting said contacts of said electrodes and face to electro-forming treatment, further adjusting each electrode in a direction normal to said face to produce a given increase of said force exerted on said face, and securing each electrode in adjusted position to said support.
